DESIGN FOR A BRUSH

Harold M. Schwartz, New York, N. Y., assignor to Rubberset Company, Newark, N. J., a corporation of New Jersey

Application October 4, 1941, Serial No. 103,633

Term of patent 14 years

To all whom it may concern:

Be it known that I, Harold M. Schwartz, a citizen of the United States, residing at New York, county and State of New York, have invented a new, original, and ornamental Design for a Brush, of which the following is a specification, reference being had to the accompanying drawing, forming a part thereof, in which:

Fig. 1 is a front elevational view of a brush embodying my new design;

Fig. 2 is a top plan view of the brush shown in Fig. 1 and

Fig. 3 is an end view of the brush as viewed from the left in Fig. 1.

I claim:

The ornamental design for a brush, as shown.
HAROLD M. SCHWARTZ.
